UNITED STATES PATENT OFFICE.

CHARLES H. ATKINS, OF PALMER, MASSACHUSETTS.

STEAM TRAP.

1,422,069.

Specification of Letters Patent. Patented July 11, 1922.

Application filed May 13, 1920. Serial No. 281,106.

To all whom it may concern:

Be it known that I, CHARLES H. ATKINS, a citizen of the United States of America, residing at Palmer, in the county of Hampden and Commonwealth of Massachusetts, have invented certain new and useful Improvements in Steam Traps, of which the following is a specification.

This invention relates to improvements in steam traps, and particularly to a type of steam trap which includes a thermostatic device for operating the valve which responds to changes in pressure and temperature, and which automatically regulates the flow of water of condensation according to such changes. The invention has for an object to provide a trap of this kind which is simple in construction; one that can be easily repaired and one that will maintain the valve member in accurate alignment with the opening in the valve seat. Other objects and nature of this invention will be more fully set forth in the body of the following specifications and drawings, in which—

Fig. 1 is an elevation, partially in section, of the casing of a steam trap and showing my invention therein.

Fig. 2 is an enlarged detailed view partly in section, of the internal mechanism.

Fig. 3 is a top plan view of the rigid perforated annular member, and

Fig. 4 is a detail of the valve aligning device.

Referring to the drawings in detail: the top member of the casing is indicated at 11, and 12 indicates the bottom member of the steam trap casing both of which may be of cast iron. These members are secured together as shown, by bolts and the joint between the same is made steam tight with a

gasket. The member 12 is provided with heat radiating ribs or fins 13 for conducting or dissipating the heat away from the same. The steam inlet pipe which is in communication with the high pressure supply of steam is connected to the boss 14 and the outlet pipe for the water of condensation is connected to the boss 15. The bosses 14 and 15 it will be noticed, are in alignment with each other.

The opening in the valve seat 16 is closed, by means of the valve member 17 as shown in Fig. 1; normally, however, this valve when the trap is cold stands slightly

open to permit the flow of steam from 14 to 15 during the short interval of time that the 55 interior of the casing is not warm enough to cause the operation of the diaphragm and the attached valve 17. The thermostatic diaphragm 18, which supports the valve member 17 is secured to the rigid supporting 60 plate 19. This plate is formed with a raised annular part, as shown. It will be observed from Figs. 2 and 3, that a series of openings or steam passages *b* and *c* are provided in plate 19, these are, in turn, covered by a fine 65 mesh wire gauze screen 21 as shown on the left half of Fig. 3 and which is secured in place at its outer edge by means of the ring 22 being located in the groove 26 and at its inner edge by means of the ring 24 in the 70 groove 27. The plate 19 is formed with undercut grooves as shown in section in Fig. 2, and the ring 22 is split or cut at 23 and the ring 24 is split or cut at 25, so that they may be sprung or snapped into place for securing the wire gauze taut over the openings *b* and *c*. The wire gauze is used as a filter for the steam and this clamping arrangement enables it to be quickly replaced.

Into the rigid supporting plate 19 is 80 screwed the hollow stem 31 which is locked in position by means of the nut 32. This stem supports the thermostatic double walled expansible diaphragm 18 which is partially filled with a volatile liquid *d*. A portion of 85 the lower end of the stem 31 is burred around the upper plate 35 of the diaphragm, as shown at 37; Fig. 4 and the lower plate 36 of the diaphragm is burred around the stem 33, as shown at 38. The valve member 90 17 is screwed to the stem 33 and moves therewith.

From this construction of the diaphragm it will be noticed that the two opposite or double walled members 35 and 36 can move 95 independently of each other so as to produce great sensitiveness, thus, while the side 35 is rigidly secured to the plate 19 which is clamped in position by the cover 11 of the trap, the valve member 17 is free to move 100 with side 36. In order to insure perfect alignment with the opening in the valve seat the upwardly extending part of the plunger 34 is guided by means of the opening in stem 31. The valve member 17 can thus move 105 only in a direct line with the valve seat and

cannot be misaligned due to buckling of the plate 36.

The liquid in chamber *d* may be poured in through the opening 40 in the plunger 34 and sealed therein by the screw 39. This may be further sealed, if desired, by filling the space above this screw with solder. When steam enters the opening 14 it is filtered by the fine mesh wire gauze 21, and then passes through the openings *c* and *d* in the plate 19, filling the chamber *a*. The heat from the steam vaporizes the volatile liquid *d*, thereby causing an expansion between sides 35 and 36 of the diaphragm 18 which causes the valve 17 to seat and closes the trap until a reduction in temperature in the casing due to the presence of condensed steam causes a contraction between sides 35 and 36 due to a preponderance of pressure in the casing, thus opening the valve again to permit the discharge of the water of condensation through the opening in the valve seat. This reduction in temperature is caused by the heat of the condensed steam being radiated from the ribs 13 and the body of the trap; in practice, this action permits an intermittent flow of water of condensation through the opening 15. It is obvious that the temperature at which the device will operate can be varied by changing the character of the volatile liquid in chamber *d*; also by the resistance offered by the diaphragm itself and by the position of the valve member 17 with relation to the valve seat 16 when in the normal position.

A feature of this invention lies in the fact that the entire interior thermostatic mechanism may be removed and a new mechanism inserted in its place when the two castings of the casing have been unbolted and separated from each other.

In use it is to be understood that the operation may be stated as follows: Normally the outlet valve 17 is retained slightly raised or spaced from its seat; the steam can then pass directly through the trap. As the temperature of the diaphragm is increased, the liquid therein boils, causing the valve to close thus shutting off the flow of steam. As the temperature falls within the trap, the valve is opened by excess of pressure in the casing over pressure in the diaphragm, and the water of condensation is allowed to flow through the discharge outlet 15. It is evident that the lower part of the trap will cool first in the portion where the diaphragm is located, thus making the device more sensitive to temperature changes.

It may be stated in connection with the operation, that the expansive force of the volatile liquid in the diaphragm is greater than the outside pressure of the steam on the diaphragm, causing the valve 17 to close. The heat of the diaphragm will be conducted away by the surrounding water of condensa-

tion and by the valve 17 being in contact with the metal valve seat thus bringing the temperature of the diaphragm down and causing the valve to lift and the water of condensation to escape. The steam immediately enters surrounding the diaphragm which immediately expands and the valve is closed again thus preventing the loss of steam. It is clear that after the valve is adjusted it will operate at any steam pressure and its attendant temperature.

What I claim is:

1. In a steam trap of the class described, in combination, of a casing, a rigid plate therein, a diaphragm comprising double expandable members spaced from each other, an open ended tubular member for connecting one expandable member to said plate, a needle point valve secured to the other expandable member of said diaphragm and movable therewith, a valve seat, and means including a stem on the other expandable member which is connected to the valve and which is located for sliding movement in the open ended tubular member for the purpose of aligning said valve member with the valve seat, said stem having an opening to permit filling the space between the diaphragm with a volatile fluid.

2. In a steam trap of the class described, in combination, an expansive chamber having an inlet and an outlet port, a rigid disc in said chamber having an annular section and formed with perforations, said perforations being located in the annular section of said disc, a detachable covering of wire gauze on the disc, a diaphragm supported by said disc and a valve operated by said diaphragm and controlling said outlet.

3. In a steam trap of the class described, in combination, of an expansive chamber having an inlet and an outlet opening, a rigid disc formed with perforations, a gauze for covering the perforations, split rings for holding said gauze in place, a diaphragm supported by said disc and a valve operated by said diaphragm and controlling said outlet.

4. In a steam trap of the class described, in combination, of an expansive chamber having an inlet and an outlet port, a rigid disc in said chamber formed with a raised annular section and the said section of the disc being perforated, a gauze covering for the disc, undercut edges on said raised section, split rings fitting said under-cut edges for clamping said gauze in place, a diaphragm supported by said disc and a valve operated by said diaphragm and controlling said outlet.

5. In a steam trap, the combination, of an enclosing casing, a rigid member secured to the casing, the casing having inlet and outlet ports arranged in alignment with each other, a diaphragm having a volatile liquid therein

and secured to the rigid member, a valve secured to the diaphragm, the rigid member being located under the inlet port and having openings to permit the incoming steam 5 to directly surround the diaphragm to cause the expansion of the liquid in the diaphragm to close the valve, the construction being such that the diaphragm will be cooled si- multaneously with the interior of the casing to open the valve and will immediately ex- 10 pand to close the valve by the incoming steam, passing through the openings in the rigid member and directly into contact with the diaphragm.

CHARLES H. ATKINS.
